BUTTER DISH COVER OR SIMILAR ARTICLE

Sol Forman and Leonard Ramer, New York, N. Y.,
 assignors to Forman Family, Inc., Brooklyn,
 N. Y., a corporation of New York

Application May 26, 1950, Serial No. 10,212

Term of patent 3½ years

(Cl. D44—15)

To all whom it may concern:

Be it known that we, Sol Forman and Leonard Ramer, citizens of the United States, residing at New York city, in the county of Kings and Queens, respectively, and State of New York, have invented a new, original, and ornamental Design for Butter Dish Cover or Similar Article, of which the following is a specification, reference being had to the accompanying drawing, forming part thereof.

In the drawing

Fig. 1 is a top perspective view of a butter dish cover, showing our new design;

Fig. 2 is a cross-sectional view taken on line 2—2 of Fig. 1.

The back of the knob and the back of the cover are the same as the front.

We claim:

The ornamental design for a butter dish cover or similar article, as shown and described.

SOL FORMAN.
 LEONARD RAMER.
